CLAIM

I claim the ornamental design for a taillight lens cover for a vehicle, as shown and described.

DESCRIPTION

FIG. 1 is a top plan view of taillight lens cover for a vehicle showing my new design;

FIG. 2. is a front elevational view thereof;

FIG. 3 is a left side elevational view thereof; and,

FIG. 4 is a left perspective view thereof.

The “taillight lens cover for a vehicle” is on the left side of the vehicle thereof; the right taillight design is a mirror image of the left side taillight design.
